(57) **CLAIM**

The ornamental design for a treadmill as shown and described.

DESCRIPTION

FIG. 1 is a rear, left, top perspective view of the treadmill, showing my new design;

FIG. 2 is a front, left, bottom perspective view thereof;

FIG. 3 is a left side view thereof;

FIG. 4 is a right side view thereof;

FIG. 5 is a front plan view thereof;

FIG. 6 is a rear plan view thereof;

FIG. 7 is a top plan view thereof;

FIG. 8 is a bottom plan view thereof;

FIG. 9 is a rear, left, top perspective view of the treadmill, shown in an alternate configuration;

FIG. 10 is an enlarged view of the area labeled 10 in FIG. 1;

FIG. 11 is an enlarged view of the area labeled 11 in FIG. 2; and,

FIG. 12 is an enlarged view of the area labeled 12 in FIG. 5.

The broken lines in the drawings illustrate portions of the treadmill that form no part of the claimed design. The dot-dash broken lines encircling portions of the treadmill in FIGS. 1, 2, and 5 illustrated in enlarged views in FIGS. 10, 11, and 12 form no part of the claimed design.

1 Claim, 12 Drawing Sheets
